UNITED STATES PATENT OFFICE.

WILLIAM J. KNORRE, OF SPOKANE, WASHINGTON, ASSIGNOR OF ONE-HALF TO
GROVER C. EALY, OF SPOKANE, WASHINGTON.

MOTION-PICTURE APPARATUS.

Application filed June 12, 1926. Serial No. 115,630.

My present invention relates to improvements in motion picture apparatus and is designed as an automatic annunciator for indicating to the operator of the apparatus 5 or machine the approaching end of the un-winding picture strip on its revolving reel. As is well known two projecting machines are usually employed for showing a long picture, and the operator or operators are required to shift their operations from one 10 projecting machine to the other as one reel is exhausted and the second reel brought into operation to insure a continuous picture on the screen. In order to ascertain the 15 proximity of the approaching end of a reel or picture strip, it is the usual practice for the operator to frequently open the cabinet door and inspect the unwound strip. This inspection requires the time and attention of 20 the operator with resulting neglect to the picture, inconvenience to the operator and uncertainty as to existing conditions within the machine cabinet.

The primary object of my invention is the 25 provision of means for automatically announcing at a predetermined time the approach of the end of an unwinding picture strip in order that the second projecting machine or apparatus may be made ready 30 and brought into use at the proper time for insuring the continuous showing of the picture on the screen.

The invention contemplates an announcing 35 device in the form of an attachment which is applicable for use with existing projecting machines without substantial alteration thereof.

The attachment is constructed and arranged so that it may be set by the closing 40 of the cabinet door, and co-acts with the picture strip on the unwinding reel in such manner that the annunciator, as a bell, is sounded as a signal when the thickness of the picture strip on the reel reaches a pre-determined minimum, thus indicating the 45 approaching end of the picture strip.

The invention consists in certain novel 50 combinations and arrangements of parts as will hereinafter be more fully set forth and claimed.

In the accompanying drawings I have illustrated one complete example of the physical embodiment of my invention wherein the parts are combined and arranged according to the best mode I have thus far

devised for the practical application of the principles of my invention. An alternative setting bolt is also illustrated which adapts the attachment for use in an alternative type of machine cabinet.

Figure 1 is a view in side elevation of the attachment set for operation with a round or circular form of cabinet, showing the relation of the attachment to the reel and picture strip wound thereon.

Figure 2 is a top plan view of the device set for operation, and showing in section a portion of the cabinet and its hinged door.

Figure 3 is a perspective view of the device showing two slide bolts for alternate use in setting the device in a round cabinet and in a square cabinet.

Figure 4 is a face view of the device adapted for use with a square machine-cabinet. Figure 5 is a detail view of the bell trip.

In order that the general arrangement and relation of parts may readily be understood I have shown in Figures 1 and 2 a portion of an unwinding reel 1 with the unwound picture strip 2 thereon located within the machine-cabinet 3. This machine cabinet is of the round or circular type and is provided with a door 4 having a hinge 5 and off-set hinge joint 6. In using the attachment with this type of cabinet the hinge 5 is used for setting the device, while the hinged door 4' of Figure 4 is used to set the device when the latter is used with a square or rectangular machine cabinet. In either case the annunciator is set for operative position with relation to the picture strip 2 on the reel, when the door is closed, and the annunciator is automatically actuated when the thickness of the picture strip reaches a minimum on the reel, thus indicating the approach of the end of the unwinding picture strip.

In carrying out my invention I utilize an attaching plate or base plate 7 which is affixed at the exterior side of the cabinet by means of screws 8 passed through the wall of the cabinet from the interior and through screw holes 9 in the plate.

The attaching plate is fashioned with an angular flange 10 extending in a line parallel with the edge of the cabinet and provided with a perforated bearing lug 11 in line with an opening or hole 12 in the base plate 7. A rock shaft 13 is supported exterior of the

cabinet in the lug 11 and passes through the hole 12 and a complementary hole fashioned in the wall of the cabinet. Within the cabinet the rock shaft is provided with an 5 arm 14 which is located between the wall of the cabinet and the periphery of the picture strip 2 on the reel, and conforms generally to the contour of the strip.

One end of the arm is inserted in or passed 10 through a transverse hole in the shaft and a set screw 15 is threaded longitudinally into the end of the shaft to engage the arm and hold it in adjusted position relative to the shaft. At its upper free end the arm 15 has a forked bearing 16 for a friction roller 17, preferably of rubber that lightly contacts with the periphery of the picture strip and permits the strip to unwind without interruption therefrom. As the thickness of the 20 strip on the reel diminishes the roller remains at all times in contact with the strip and thus gradually turns its rock shaft 13 in a clockwise direction through a suitable angle for the purpose of actuating the annunciator as will be described.

The rock shaft is provided with an adjustable screw 18 threaded transversely therethrough exterior of the cabinet and the angle plate 10 is slotted at 18' to give access 30 to the screw for turning. The end of the screw is pointed as at 19 and this point contacts with a pivoted detent 20 on a lever 21 having a tapper 22 for the bell 23. The lever arm is pivoted exterior of the cabinet 35 at 24 on an adjustable plate 25 which is forked or slotted for use with a fastening screw 26 which secures the plate in adjusted position on the attaching plate 7 of the device. The bell is also adjustably supported 40 from the plate 7 by means of the bell-plate 27 which is slotted or forked for the fastening screw 28. The pivoted lever with its tapper and the bell are thus relatively adjustable to secure the ringing action of the bell. A 45 spring 29 is used to afford a resilient support for the bell tapper.

The rock shaft and arm 14 are provided with a counterbalance weight 30 carried on the stem 31 which has a threaded end 32 50 and is passed through a threaded opening in the rock shaft. The weight may be adjusted with relation to the arm and its roller so that the arm and roller will overbalance the weight, thus permitting the arm and 55 roller, when free, to swing the rock shaft and maintain the roller in contact with the periphery of the picture strip on its reel.

In setting the device the rock shaft is released in order that the arm and roller may 60 swing by gravity to bring the roller in contact with the picture strip and this swinging of the roller and arm turns the shaft to bring the point 19 of the screw into contact with the free end of the pivoted detent on 65 the bell lever 21. As the thickness of the pic-

ture strip diminishes the roller and arm causes a gradual turning movement of the rock shaft and the screw point 19 causes an upward swing of the bell tapper 22. When the roller has swung to the proper angle 70 determined by the minimum thickness of the picture strip the screw point 19 swings past and below the detent 20, thus freeing the bell tapper and the latter falls upon the bell 75 23 to give a warning signal to the operator. In re-setting the device, the pivoted detent permits the screw point to swing past it as indicated by dotted lines in Figure 5.

The angle plate 10 is slotted as at 33 for the accommodation of the arm or stem 31 of 80 the counterweight 30.

The annunciator device is automatically set through the instrumentality of the hinge plate 5 as the door 4 is closed or swung to closed position on its hinge joint 6. The hinge plate co-acts with a slide bolt 34 located exterior of the cabinet and positioned parallel with the rock shaft. The bolt is 85 slidable in perforated bearing lugs 35 and 36 of the angle plate 10, and at its end adjoining the door of the cabinet is provided with an adjustable screw 37 threaded longitudinally in the bolt, a lock nut 38 being employed to secure the screw in adjusted 90 position. The hinge plate 5 is adapted to contact with the screw head and slide the bolt, as the door is closed, against the tension of a spring 39 located between a fixed collar 40 on the bolt and one of the bearing lugs 95 as 36.

At its opposite end the slide bolt carries a lever 41 which is pivoted at 42 on the angle plate 10 and fashioned with a forked or slotted end 43 for pivotal connection with the pin 44 extending transversely through the slide bolt. The lever arm is fashioned with a curved or cam face 41a on its under edge, which, when the bolt is sprung to open position, rests upon the arm 31 of the counterweight, holding said arm down, and the arm 14 and roller 17 up. When the slide bolt is pushed toward the observer as in Figure 2 and to the right as in Figure 4, its movement swings the lever 41 on its pivot 42 115 withdrawing the lever from the arm 31 and thus permitting the roller 17 and arm 14 to overbalance the weight 30 and swing the rock shaft to engage the screw point 19 with the bell lever or with the pivoted detent on the lever. The bell lever is thus set for operation when the thickness of the picture strip diminishes to the predetermined minimum.

After the annunciator has been actuated and the door 4 is opened, the spring 39 120 slides the bolt 34 causing the cam lever 41 to ride down the arm 31 of the counterweight, rock the shaft 13, and swing the roller 17 free of the reel.

When the device is attached for use with 125 motion picture apparatus using rectangular

or square cabinets and hinged doors of a type different than that used in the round cabinets, the door 4' of the cabinet is used to set the device, and a slide bolt 45 for alternate use is substituted for the slide bolt 34. This slide bolt 45 is supported in a perforated bearing lug 46 of the angle plate 10 and passes through an opening in the attaching plate 7 and the wall of the cabinet. The screw 47 at the end of the bolt is located within the cabinet and the door 4' is adapted to contact therewith as indicated in Figure 4. The pin 44 used on the slide bolt 34 also passes through this second bolt, and the bolt, through the pin actuates the cam lever 41 in manner similar to the movement imparted thereto by the action of the slide bolt 34.

The two slide bolts are for selective use, and of course only one bolt is used to actuate the cam lever, both for releasing the roller and its arm to set position and for retracting the roller when the door of the cabinet is opened. As long as the door is closed the cam lever is held free of the weight arm 31 and the latter is free to swing with the rocking movement of the rock shaft 13.

Having thus fully described my invention what I claim as new and desire to secure by Letters Patent is—

1. The combination with an annunciator and its actuating means, of a rock shaft hav-

ing a detent for co-action with said means, an arm on the rock shaft and a friction element on the arm for co-action with an unwinding picture strip, an opposed counterweight on the shaft, a setting bolt, and means operated by the setting bolt for co-action with the counterweight for setting the rock shaft in operative position.

2. An attachment for a motion picture apparatus comprising an annunciator and a gravity actuated device co-acting with an unwinding picture strip for actuating the annunciator, retaining means for holding said gravity actuated device in inoperative position while the door of the apparatus is open, and a slide bolt actuated by the closing door for releasing the retaining means.

3. The combination in an attachment for motion picture apparatus with an annunciator and its actuating means, of a rock shaft having a detent for co-action with said means, an arm on the rock shaft and a friction element on the arm for co-action with an unwinding picture strip, a pin on the shaft and a counterweight on the pin, a setting bolt actuated by the closing of the door of the apparatus, and a lever on the bolt for co-action with said pin for setting the rock shaft in operative position.

In testimony whereof I affix my signature.

WILLIAM J. KNORRE.
